US00D872601S

(12) **United States Design Patent** (10) Patent No.: **US D872,601 S**
(45) Date of Patent: ** Jan. 14, 2020

(54) **CONCRETE MEASURING INSTRUMENT**

(71) Applicant: **PROCEQ AG**, Schwerzenbach (CH)

(72) Inventors: **Reto Tremp**, Benken (CH); **Simon Bürdel**, Aarau (CH); **Patrick Waller**, Dübendorf (CH); **Marcel Poser**, Oberuzwil (CH); **Roman Schnell**, Basel (CH); **Ralph Mennicke**, Uster (CH)

(73) Assignee: **PROCEQ AG**, Schwerzenbach (CH)

(**) Term: **15 Years**

(21) Appl. No.: **35/504,987**

(22) Filed: **Nov. 24, 2017**

(80) **Hague Agreement Data**

Int. Filing Date: **Nov. 24, 2017**

Int. Reg. No.: **DM/099991**

Int. Reg. Date: **Nov. 24, 2017**

Int. Reg. Pub. Date: **May 25, 2018**

(30) **Foreign Application Priority Data**

Jun. 22, 2017 (CH) 143339

(51) **LOC (12) Cl.** **10-07**

(52) **U.S. Cl.**

USPC **D10/47**

(58) **Field of Classification Search**

USPC D10/47; D24/222

See application file for complete search history.
